United States Patent Office

Des. 197,943
Patented Apr. 7, 1964

197,943

BALL COCK

Alvin E. Jacobson, Jr., Grand Haven, Mich., assignor to
Grand Haven Brass Foundry, Grand Haven, Mich., a
partnership

Filed Jan. 15, 1962, Ser. No. 68,383

Term of patent 14 years

(Cl. D91—3)

FIG. 1

FIG. 2

FIG. 3

FIG. 1 is a side elevational view of the ball cock showing my new design;

FIG. 2 is a front elevational view thereof; and

FIG. 3 is a top plan view thereof.

I claim:

The ornamental design for a ball cock, substantially as shown.
